UNITED STATES PATENT OFFICE.

JAMES C. DAVIS, OF HINSDALE, ILLINOIS, ASSIGNOR TO AMERICAN STEEL FOUNDRIES, OF NEW YORK, N. Y., A CORPORATION OF NEW JERSEY.

METHOD OF AND APPARATUS FOR VENTING MOLDS.

1,157,847.

Specification of Letters Patent.

Patented Oct. 26, 1915.

Application filed April 22, 1915. Serial No. 23,038.

To all whom it may concern:

Be it known that I, JAMES C. DAVIS, a citizen of the United States, and resident of Hinsdale, in the county of DuPage and State 5 of Illinois, have invented certain new and useful Improvements in Methods of and Apparatus for Venting Molds, of which the following is a specification.

This invention relates to a novel method 10 of venting molds and has for its object the location of a vent conduit which will be of a certain definite size and accurately located at all times with respect to the mold cavity and which will further be simple and inexpensive enough to warrant its adoption in general practice.

Under certain conditions of casting steel, due to peculiar characteristics of designs, the 20 temperature or composition of the metal, the density and condition of the sand structure in the mold, porosity is encountered on the surface of the resultant casting. This is especially true where the metal is run into thin sections and where extreme solidity is desired, such for instance as members which 25 are normally under tension when under service loading. The object of my invention is to provide means which will prevent the formation of porosity on the surface of these 30 important members, especially where the product is a specialty or the work is duplicate so that it is possible to standardize in the matter of venting. To a large extent solidity in structure can be induced by providing suitable vents for carrying off the 35 gases from the sand in immediate contact and in close proximity to the metal in that member of the casting. It has been found that by proper location of the vent and by 40 proper graduation in size it is possible to eliminate the objectionable surface porosity from the resultant castings.

The preferred form of my invention is shown on the accompanying drawings and 45 described in the specification but there is no intention to limit the invention to the precise apparatus shown as considerable modification may be made without departing from the scope and spirit thereof.

50 The invention will be more fully understood by reference to the accompanying drawings, wherein, Figure 1 is a plan sectional view of a mold taken on the line "A—A", of Fig. 2 the sand being omitted; Fig. 2 is a cross section taken on the line

"B—B", of Fig. 1 the sand being shown; Fig. 3 is a perspective view of a portion of the pattern showing the vent rod held in position; Fig. 4 is an enlarged cross section on the line "C—C" of Fig. 1, and Fig. 5 is 60 a longitudinal section on the line "D—D", of Fig. 4.

In the drawings 10, indicates a half pattern of metal, mounted on a flat match plate 11. The design of pattern 10, is shown as 65 simple as possible to clearly illustrate the features of my invention but a pattern of any design regardless of complexity may be similarly adapted and changed to embody the principles of my invention.

A flask 12, of the usual construction is then placed on the match plate and located with respect to the pattern by means of the flask pins. These flasks are provided with holes 13, which are of size and location dependent upon the design of the casting produced by the mold.

On the pattern are placed suitable lugs or prints 14; these may be fastened on or cast or formed integral with the pattern as desired. These lugs or prints 14, are provided with draft as clearly shown in Figs. 3 and 4, so that they may be easily drawn from the sand. The prints are each provided with an aperture 15, to serve as a bearing for a 80 vent rod 16. By this means I am enabled to locate the vent rod in position with regard to the section of the casting to which they apply. The vent rod is securely held in alignment with the pattern member and 85 there is no danger of variation in position or misplacement during the operation of ramming the mold. This is an important feature as it has been found that to get the best results, the vent conduit must have some 90 definite relation to the metal section. By the method already explained, this relation when established is permanent and no variation can occur as the vent has been so standardized that results can be secured with ordinary unskilled molding labor.

The vent rods 16, are provided with suitable handles 17, so they can be drawn manually from the flask at the proper time. The pattern provides a mold cavity 18, in the 105 sand forming the mold and small stop-off cores 19, are employed to close off the recesses formed by prints 14.

The manner of carrying my invention into practice is as follows: The flask 12, is placed 110

on the match plate so as to surround the pattern in the ordinary way and located in position by means of the usual flask pin arrangement. The vent rods 16, are now inserted through the holes in the sides of the flask and are then threaded through apertures 15, in lugs 14, attached to the pattern.

When the vent rods are all in position, the flask is filled with facing and backing-up sand and rammed up. The vent rods 16, are now drawn out of the mold and the flask lifted off the pattern or the plate rolled over and the pattern drawn out of the mold, or stripped out of the sand, depending on how molding equipment is employed. The mold is now ready for coring and such finishing as necessary. It will be apparent that when the pattern is drawn from the mold there will be impressions in the sand corresponding to the prints 14, and these must be stopped off with the cores 19, so that the mold cavity has the requisite shape and contour as demanded in the finished casting. These cores 19, being provided with a recessed bottom 25 surface 20, do not interrupt the continuity of the vent conduit hitherto formed in the sand by the vent rods.

I claim:

1. The method of molding which consists 30 in placing a pattern in a flask, locating a venting tool in proximity to and in substantial parallelism with an edge of the pattern,

ramming sand around said pattern and between said tool and pattern, removing said pattern and tool, said tool being withdrawn 35 lengthwise to provide a vent opening alongside and substantially parallel with the pattern and out of communication with the casting space, substantially as described.

2. In apparatus for molding, the combination of a flask containing sand, a pattern in said flask, and a rod lying alongside and substantially parallel to an edge of said pattern, said rod upon removal being adapted to provide a vent opening substantially parallel 45 with the edge of the casting to be formed, substantially as described.

3. In apparatus for molding, the combination of a flask containing sand, a pattern, a venting tool associated with and located 50 substantially parallel to an edge of said pattern and maintained in proper relation thereby, said tool being adapted for removal separately from said pattern thereby leaving a venting space alongside said casting and out 55 of communication with the casting space, substantially as described.

Signed at Chicago, Illinois, this 16th day of April, 1915.

JAMES C. DAVIS.
